UNITED STATES PATENT OFFICE.

JOSEPH BROOKS DAVIS, OF KNOXVILLE, TENNESSEE, ASSIGNOR OF ONE-HALF TO ALEXANDER ANDERSON SCOTT, OF SAME PLACE.

CAR-COUPING.

SPECIFICATION forming part of Letters Patent No. 550,340, dated November 26, 1895.

Application filed August 17, 1895. Serial No. 559,646. (No model.)

To all whom it may concern:

Be it known that I, JOSEPH BROOKS DAVIS, a citizen of the United States, residing at Knoxville, in the county of Knox and State 5 of Tennessee, have invented certain new and useful Improvements in Car-Couplers, of which the following is a specification.

My invention relates to improvements in car-couplers, and has for its object to provide 10 a device that will automatically couple the cars, and will at the same time effectually prevent their accidental uncoupling.

A further object of my invention is to reduce to a minimum the number of parts required to perform the work, thus decreasing 15 the liability of the device becoming inoperative and at the same time cheapening the cost of manufacture.

These objects I accomplish in the manner 20 and by the means hereinafter described and claimed, reference being had to the accompanying drawings, in which—

Figure 1 is a vertical longitudinal section 25 of a draw-head, showing the coupling-link in position to enter the same. Fig. 2 is a similar view showing the link part way in. Fig. 3 is a similar view showing the link coupled herein.

In the said drawings the numeral 1 denotes 30 the draw-head of a car, which may be connected thereto in any suitable manner, and which is provided with the flaring mouth, as usual. Within said draw-head there is located the longitudinally-movable block 2, recessed along a portion of its top surface, as shown, and having its front end slightly beveled or inclined upwardly and inwardly. This block is normally projected to its forward position by the spring 3. A pin 5, fastened to said block, passes through a longitudinal slot 6 in the bottom of the draw-head, and has fastened thereto a cord or chain 7 for retracting said pin and block against the tension of the spring 3, when desired, and also 40 limits the forward movement of the block. The upper inner face of the draw-head is also provided with a recess 8, as shown, for a purpose hereinafter to be described.

The coupling bar or link I employ is of the 45 shape shown, consisting of the longitudinal portion 9 with its ends rounded, and provided

with the inwardly-facing shoulders 10 on its top side.

From the above description the operation 55 of my device will be understood to be as follows: When it is desired to couple up two cars, they are brought together, the link being carried by one of the draw-heads, and as its free rounded end impinges against the sliding block 2 it forces the same back against 60 the pressure of the spring 3 until the shoulder 10 thereof passes beyond the outer edge of the recess 8 in the draw-head, whereupon the end of the link will, by reason of the inclined face of the block 2, at once slip up into 65 said recess 8, and as there is provided sufficient room for the accommodation of the body of the link between the underside of the draw-head opening and the top of the block 2 the said block will be at once forced forward 70 again, thus firmly retaining the link against accidental disengagement from the draw-head, as shown in Fig. 3. Now when it is desired to uncouple the cars it is only necessary to retract the block 2 by means of the pin 5 75 and cord or chain 7, whereupon the link will drop of its own weight from engagement in the recess 8 and can be readily withdrawn.

By means of the aperture 4 in the draw-head it may, if desired, be used with the ordinary link and pin. (See Fig. 1.)

In my drawings and description I have only shown one draw-head; but it will be readily understood that the link is coupled at its other end in the same manner to the draw-head of the adjacent car.

Having thus described my invention, what I claim is—

1. In a car coupler, the combination with a draw head having a recess in its upper surface, 90 and a spring pressed block in said draw head resting upon the bottom of said draw head and normally projected beyond said recess, of a coupling link having shouldered ends and adapted to force said block back far enough 95 to permit its entrance into said recess, the said block passing forward again beneath the link to retain it in said recess, substantially as shown and described.

2. In a car coupler, the combination with a 100 draw head having a recess in its inner upper surface, a spring pressed block in said draw

head resting upon the bottom of said draw head and recessed on its front top surface and having its outer end beveled upwardly and inwardly, and a pin projecting through the bottom of the draw head for retracting said block, of a link having shouldered ends and adapted to press back the block and engage in the angular recess in the draw head, the

10 said block moving forward again to retain said link in its engaged position, substantially as shown and described.

JOSEPH BROOKS DAVIS.
